UNITED STATES PATENT OFFICE

1,983,994

PLASTER BED

John S. Raynor, Holmesburg, Pa.

Application July 9, 1931, Serial No. 549,651

6 Claims. (Cl. 72—124)

My invention relates to new and useful improvements in a plaster bed, such as is often known as lath or plaster key and one of the objects of the invention is to dispose a key element over a sheet or block of material, said key element being fastened to the sheet by bending the edges of the key element over the edges of the sheet.

To carry out the above mentioned object, I prefer to use a sheet of relatively stiff material, such as straw-board, card-board or plaster-board and the like over one or both faces of which is disposed sections or areas of a foraminous material which preferably has sufficient inherent stiffness to hold said section of material and the load of applied plaster by bending the edges of the section or sections of foraminous material over the edges of the sheet material and against the opposite face of the latter.

While I have named a number of the foraminous key forming elements, it is to be understood that any equivalents may be utilized, such as punched paper stock with or without concaved or convexed cupped portions, welded or woven wiring, expanded metal, woven fabric, vegetable matter formed into rough surfaced keys, sheet steel punched fashioned or formed into any suitable configuration or key element design or combinations of wires and material of vegetable base in combination with each other, such as straight or woven wire and burlap or matting.

In actual experiments that I have so far made, I have found it possible to use ordinary poultry wire, expanded metal, welded wire, woven wire, knitted wire, stitched wire, riveted wire, slotted wire, punched or perforated sheets of metal or paper stock, sheet steel with cupped-up portions, sheets of combined metal and vegetables or other composite materials, pressed composition sheets, knitted or woven vegetable matter such as burlap netting and screening, matting formed from seaweed so long as the material has inherent strength to support itself and a load of applied plastering over its entire area when attached only by its edges to the edges of the supporting sheet and providing the formation or configuration is such that it offers a grip to permit plaster to be rounded over, cupped into, wedged into, or laid over, portions thereof until the applied plaster becomes stiff or has progressed to some extent into the hardening state.

Another object of my invention is to provide a plaster bed consisting of a supporting sheet of fairly stiff material and a section of key element also of stiff material disposed across one

face of the supporting sheet and having the edges thereof bent over the edges of the supporting sheet and engaging the opposite face thereof.

A further object of the invention is to provide a plaster bed consisting of a sheet of material, a key element disposed across one face of the supporting sheet and bent over the edges thereof so as to contact with the opposite face and means for securing the bent over or turned over edges of the key element to the supporting sheet.

A still further object of the invention is to provide for supporting intermediate parts of the key element.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is a fragmentary perspective view of a plaster bed embodying my invention.

Fig. 2 is an enlarged fragmentary sectional view showing one manner of bracing or anchoring the key element within the body thereof or at distances from the edges.

Fig. 3 is a similar view showing another method of bracing or anchoring the key element and illustrating another form of key element.

Fig. 4 is a further enlarged fragmentary sectional view along a line such as 4—4 of Fig. 1, showing one method of attaching the plaster bed to a support, such as a stud or rafter.

Fig. 5 is a similar view as though taken at the line 5—5 of Fig. 1.

Fig. 6 is also a similar view as though taken at the line 6—6 of Fig. 1.

Fig. 7 is a perspective view of a plaster bed embodying the simplest form of my invention looking toward the obverse face of the supporting sheet over which the main body of the key element is disposed.

Fig. 8 is a fragmentary reverse face view thereof on a slightly reduced scale.

Fig. 9 is a perspective view of a section of another form of the invention.

In carrying out my invention as herein embodied, 10 represents a supporting sheet such as plaster-board, card-board or stiff paper over one face of which is disposed a section of key element 11, preferably wire fabric or other foraminous metallic structure, although equivalents and

substitutes can be utilized, examples of which have been herein before set forth. The edges of the key element are turned, bent or formed over the edges of the supporting sheet to produce gripping flanges or rims 12. The main body portion of the key element is sufficiently slack to permit applied plaster to pass through the key element and occupy the space between said key element and the contiguous face of the supporting sheet.

10 This not only makes a positive key for the plaster but has the additional advantage of causing said key element to be entirely covered by or embedded in the plaster to prevent the deteriorating action of the elements thereon.

15 In some instances, especially where the supporting sheet is of exceedingly large area, it is advisable to further support the key element, brace or anchor the same on the support sheet and therefore staples 13 may be driven directly through the

20 key element and the supporting sheet and the ends clinched. In the case of wire fabrics, such as poultry wire or window screening, the staples straddle a strand of the fabric, but in the case of perforated material the legs of each staple will 25 pass through adjacent perforations and in some material the legs of the staple may make their own apertures as they are driven through the key element and the supporting sheet.

The key element can also be braced by a wire 30 14 disposed on the outside of the body of said key element and running either longitudinally or crosswise of the complete structure with the ends bent over opposite edges of the structure as indicated at 15 so that the terminals of said wire are 35 disposed against the reverse face of the structure and if found desirable, the wire 14 may be further fastened in position by staples 16 which are the same as the staples 13 but straddle the wire 14.

Wherever staples are used to secure the wire in 40 place, the ends of the wire need not be bent around the edges of the structure and I have therefore shown a wire at 17 held in place by staples 18.

It is also possible to dispose a wire or wires 19 over the reverse face of the supporting sheet as 45 shown in Fig. 2, and then drive the staples 20 through the key element and the supporting sheet so that the legs of the staples will be on opposite sides of the wire 19 and the ends of the staple legs then clinched or bent over, and if found 50 desirable, the pointed ends of the staple legs may be embedded into the supporting sheet.

In addition, wires 21 and 22 may be disposed over both the obverse and reverse faces of the structure in parallelism and staples 23 then positioned so as to straddle both of the wires and the sharpened ends of the legs are clinched or bent over as shown in Fig. 3.

In assembling, installing or erecting the plaster bed, the same is disposed over or across the face 60 of the studs, joists, rafters or other supporting devices 24 and nails 25 driven through the structure into the supporting devices and the heads of the nails bent over so as to grip any of the wires 14, 17 and 22 disposed over the obverse face 65 of the structure as shown in Figs. 4 and 5 or over a portion of the key element as illustrated in Fig. 6. Where the nail is driven through the plaster bed in the region of an end of the wire 14, it will assume a position similar to that illustrated in Fig. 4, but where the nail passes through a central body part of the device, it will have the appearance of Fig. 5, whereas if the nail is driven through the device near the edge then only the two parts of the key element on opposite 75 faces of the supporting sheet will be in the region

of the nail as shown in Fig. 6. Of course, any other method of fastening the bed in place can be utilized.

Where some material other than metal is used as the key element, as when using burlap, matting or woven textile or purely vegetable fabrics or paper which is intended to be illustrated in Fig. 9, and designated by the numeral 26, the edges of said key element 26 is carried around or disposed over the edges of the supporting sheet 10 so as to lap over the reverse face of the supporting sheet and then sewn, pasted or otherwise fixed in position and at suitable intervals within the main body area said key element may also be stitched, pasted or otherwise connected with or to the supporting sheet.

When the plaster bed units are assembled or erected, their edges abut and due to the key element passing around the edges of the supporting sheet certain spaces will be formed, and in connection with the parts of the key element passing around the edges of the supporting sheet will act as keys for the applied plaster.

One of the main advantages of the invention is the saving in cost of material and labor since 25 a plaster bed unit covering a certain area can be manufactured and delivered more cheaply than wood lath to cover the same area and the plaster can be applied evenly and in a relatively thinner mass due to the solid backing of the 30 supporting sheet and since the applied plaster will tend to adhere to the supporting sheet, it is unnecessary to provide the excess plaster which ordinarily passes between wood or metal lath thereby saving considerable material.

Of course, I do not wish to be limited to the exact details of construction herein shown and described as these may be varied within the limits of the appended claims without departing from the spirit of my invention.

Having thus fully described my invention, what I claim as new and useful is:

1. A plaster bed comprising a rigid imperforate member, and a meshed member slightly larger than the imperforate member and imposed on 45 one face thereof and having all its margins turned over the edges of said imperforate member to secure the two members together.

2. A plaster bed consisting of a supporting member, a key element disposed over the entire surface of one face of said supporting member and having its margins turned back over all of the edges of said supporting member, and means to attach the key element to the supporting member intermediate the edges thereof.

3. A plaster bed consisting of a supporting member, a key element disposed over the entire surface of one face of said supporting member and having its margins turned back over all of the edges of said supporting member, and staples projecting through the key element and supporting member to attach the former to the latter intermediate the edges thereof.

4. A plaster bed consisting of a supporting member, a key element disposed over the entire surface of one face of said supporting member and having its margins turned back over all of the edges of said supporting member, straight sections of wire disposed across the key element, and staples straddling said wire and projecting through said key element and the supporting member to fasten the parts together intermediate the edges of the supporting member.

5. A plaster bed consisting of a supporting member, a key element disposed over the entire

surface of one face of said supporting member and having its margins turned back over all of the edges of said supporting member, straight sections of wire disposed across the face of the 5 supporting member opposite the face over which the main part of the key element is disposed, and staples projecting through said key element and the supporting member and clinched about the sections of wire to fasten the parts together intermediate the edges of the supporting member.

10 6. A plaster bed consisting of a supporting member, a key element disposed over the entire surface of one face of said supporting member

and having its margins turned back over all of the edges of said supporting member, straight sections of wire disposed across the key element, other straight sections of wire disposed across the face of the supporting member opposite that over which the main portion of the key element is disposed, and in juxtaposition to the first mentioned wire sections, and staples projecting through the key element and supporting member and straddling corresponding opposite wire sections, said staples engaging the wire sections to fasten the parts together.

JOHN S. RAYNOR.
